UNITED STATES PATENT OFFICE.

GUSTAV FUCHS, OF CHICAGO, ILLINOIS.

DESIGN FOR AN ADVERTISING-POST.

SPECIFICATION forming part of Design No. 14,140, dated July 31, 1883.

Application filed June 12, 1883. Term of patent 3½ years.

To all whom it may concern:

Be it known that I, GUSTAV FUCHS, a citizen of the United States of America, residing at Chicago, in the county of Cook and State of Illinois, have invented and produced a new and original Design for Advertising-Posts, of which the following is a specification, reference being had therein to the accompanying drawing.

10 The drawing represents an elevation of my advertising-post that is made in imitation of a telegraph-post.

A denotes the post, having bolted to its lower end three or four feet, B, which consist of iron bars bent angular for forming a broad base.

15 C C' C' are boards secured at their middles transversely against the upper portion of the post, to be parallel with each other. These boards C C' C' are of decreasing lengths toward the top, and each has fastened upon its

upper edge a series of bells or shields, a, imitating the insulating glass thimbles that are generally used for holding telegraph-wires. Such a bell or shield is also secured upon the upper extremity of the post. Names, letters, 25 or words are painted upon the boards C C' C', and also on the shields or bells.

I claim—

The design for an advertising-post made in imitation of a telegraph-post, and consisting 30 of post A, with feet B, and transverse sign-boards C, with shields or bells a, all substantially as herein shown and described.

In testimony whereof I affix my signature in presence of two witnesses.

GUSTAV FUCHS.

Witnesses:

LOUIS NOLTING,
ADAM GEO. WHITE.
